UNITED STATES PATENT OFFICE.

FRANK MAAS, OF SPRINGFIELD, MISSOURI.

RAILWAY-RAIL CLAMP.

1,069,447.

Specification of Letters Patent.

Patented Aug. 5, 1913.

Application filed April 23, 1912. Serial No. 692,564.

To all whom it may concern:

Be it known that I, FRANK MAAS, a citizen of the United States, residing at Springfield, in the county of Greene and State of Missouri, have invented certain new and useful Improvements in Railway-Rail Clamps, of which the following is a specification.

My invention relates to improvements in railway rail clamps and pertains particularly to those adapted to be used on metallic or concrete ties.

The object of my invention is to provide a rail clamp in which the rail can be readily inserted and one which will firmly hold the rail on the tie.

Another object of my invention is a rail clamp which can at any time be tightened without disturbing the rail and at the same time providing a simple, cheap and effective clamp having certain details of structure hereinafter more fully described.

My invention will be described in detail hereinafter and illustrated in the accompanying drawings in which—

Figure 1 is a top plan view of my improved rail clamp applied to a tie. Fig. 2 is a vertical sectional view showing the rail clamped thereby. Fig. 3 is an edge view of the two clamping members, and Fig. 4 is a plan view of one of the clamp operating blocks.

Referring now to the drawings 1 represents a plate which is secured in a metallic or concrete tie 2 in any desired manner and which has at each end the downwardly extending end walls 3 and 4. Mounted in the side walls 5 of the said plate is a bolt or rod 6 upon which are mounted the rail clamps 7 and 8. The clamp 7 has its lower end bifurcated and the arms 9 and 10 are provided with oppositely arranged openings 11 through which the bolt or rod 6 passes. The lower end of the rail clamp 8 is reduced in thickness so that it will freely pass between the two arms 9 and 10 of the bifurcated end of the clamp 7 and is provided with an opening 12 through which the bolt or rod 6 passes.

The upper ends of the rail clamps are provided with inwardly extending lateral ends 13 and 14 which extend through an elongated opening 15 in the plate 2 and are adapted to clamp the upper face of the base 16 of the rail 17. The formation of the lower ends of the rail clamps allows the two

laterally turned upper ends to engage the base of the rail exactly opposite each other.

The rail as shown in Fig. 2 rests upon the plate 2 across the center of the opening 15 and the rail clamps extend through said opening on each side of the base of the rail. In order to firmly hold the rail clamp in the position shown in Fig. 2, I provide the upper face of the plate 2 with small openings 18 and 19 adjacent the ends of the elongated opening 15. Below said plate are arranged the clamping blocks 20 and 21 which are of the shape shown in Figs. 2 and 4. The said blocks are of a width equal to the thickness of the rail clamp and have their inner edges beveled as indicated at 22 which are adapted to engage the outer edges of the two rail clamps 7 and 8. The outer edges of the blocks are straight as indicated at 23 and are adapted to engage the vertical end walls 3 and 4 of the plate 1. The blocks are provided with vertically disposed screw-threaded openings 24 and 25 into which are screwed the screw-bolts 26 and 27. These bolts pass downwardly through the openings 18 and 19 and have their heads bearing against the upper face of the plate.

The blocks having the beveled faces 22 bearing against the rail clamps it will be seen that by screwing the bolts in, the blocks are drawn upwardly and their beveled edges forced against the clamps which clamp the base of the rail; the end walls of the plate 90 preventing the outward movement of blocks. The unscrewing of the bolts allows the blocks to drop by force of gravity and then the rail clamps by force of gravity will move outwardly and release the rail.

This structure of a rail clamp allows of the tightening of the same at any time without disturbing the rail and also allows for the proper adjustment of the rails to or from each other to obtain the proper gage. 100 This can be accomplished by forcing one block down on one side and drawing the other block up on the other side.

Having thus described my invention, what I claim is—

1. A device of the character described, comprising a housing having a slot in its upper end, pivoted rail clamps mounted in the lower end of the housing and extending through said slot, blocks within the housing 110 for operating said clamps, and screw bolts passing through the upper end of the hous-

ing for raising and lowering said blocks, substantially as shown.

2. A device of the character described, comprising a housing having a slot in its upper end, pivoted rail clamps mounted in the lower end of the housing and extending through the slot, blocks within the housing and having beveled ends engaging the outer edges of said clamps, and bolts passing through the upper end of the housing and screwed into said blocks, whereby the blocks are drawn upwardly for forcing the clamps inwardly.

3. A device of the character described, comprising a housing having a slot in its upper end, a horizontal bolt in said housing, rail clamps mounted on said bolt and extending through the slot, blocks within the housing and having vertical outer ends engaging the housing and beveled inner ends engaging the rail clamps, and screw-bolts passing loosely through the upper end of the housing and screwed into the blocks whereby the blocks are drawn upwardly for forcing the rail clamps inwardly.

4. A device of the character described,

comprising a housing having an elongated longitudinal slot in its upper end, a horizontal bolt in the lower end of the housing, a rail clamp having a bifurcated lower end, the arms of which have oppositely arranged openings through which the bolt passes, a second rail clamp having a reduced lower end mounted on the bolt between the arms of the bifurcated end of the first mentioned clamp, the upper ends of the clamps extending through the slot in the upper end of the housing, blocks within the housing and having vertical outer ends engaging the side walls of the housing and beveled inner ends engaging the rail clamps, and screw-bolts passing through openings in the upper end of the housing and screwed into the blocks whereby the blocks are drawn upwardly for forcing the rail clamps inwardly.

In testimony whereof I hereto affix my signature in the presence of two witnesses.

FRANK MAAS.
